METHOD FOR CHIROPRACTIC ADJUSTMENT

Joseph Clay Thompson, Davenport, Iowa

Application January 30, 1953, Serial No. 334,159

5 Claims. (Cl. 128—69)

My invention relates to an improvement in the healing 15 art as applied by the chiropractic profession in adjusting subluxations of various patients, more particularly in the upper cervical region.

The objects of my invention are:

1. To provide a method or process for adjustment of 20 the occiput, atlas, axis or third cervical vertebra, any or all of them, in a manner which will greatly lessen or avoid the pain a patient is frequently caused to suffer from a vigorous application of force for adjustment of subluxations in that region;

2. To provide such a method of adjustment of increased and superior effectiveness and accuracy for removing subluxations of the cervical region of the spinal column;

3. To provide a method of adjustment which will be 30 useful in reducing and effective in avoiding or preventing overadjustment of subluxations or misalignments and the bad effects resulting therefrom;

4. To provide a method of adjustment which will enhance and improve the effect of recoil and reduce or avoid 35 excessive recoil of any of the parts involved, and which will reduce the number of adjustments necessary in most cases;

5. To provide a method for adjustment of spinal subluxations which can be readily learned and applied by chiropractors and students of chiropractic, and which will afford the less skillful chiropractors power to afford the relief of the more skillful.

6. To provide a method of chiropractic adjustment of subluxations in the cervical region of human beings which includes the application of manual force to the neck of a patient while his head and neck are resting upon a specific resilient headpiece adapted to allow a limited downward movement of the head and neck of the patient under adjusting force applied by the operator and to definitely stop the movement of the part of the headpiece in contact with the patient's head and neck after an adjusted length of travel thereof, with means adapted to prevent the return of the movable part of said headpiece which is in contact with the neck and head until manually released by the operator; said headpiece also being provided with resilient means to cushion the effect of the adjusting force when applied to the patient's neck.

The preferred form of my headrest is fully described in my co-pending application for patent, Serial No. 319,639 and is illustrated in the diagrammatic drawings hereto attached in which—

Figure 1 is a diagrammatic plan view of one form of headrest usable in my method;

Figure 2 shows a side view of Figure 1;

Figure 3 shows an enlarged detail of one form of locking device to hold the top plate in its lowermost position;

Figure 4 shows an alternate form of mounting the top plate upon the base plate of the headrest.

In Figures 1 and 2 the base plate 1 is shown with the top plate 2 pivotally mounted thereon upon the shaft 8 70 carried by suitable mountings 9 and 26, with helical

2

springs mounted upon bolts 12—21. Stop blocks 4 and 5 are mounted upon the base plate 1 and top plate 2 to limit the downward movement of the top plate.

A gauge bolt 24 is shown with its upper end united to the top plate 2 and extending downwardly through the base plate 1 with a wing nut 25 threaded thereon by which the distance between the top and base plates when in open position may be regulated.

In Figure 4 the top and base plates are shown hinged together at the outer end thereof with helical springs 23 mounted in suitable sockets 21 and 22 formed in the opposing faces of the top and bottom plates of the headrest.

The forms illustrated contain all the elements necessary for my method, but many modifications or variations thereof or equivalents therefor may be utilized without departing from the spirit of my invention.

To determine whether an adjustment is necessary in any given case, a careful, thorough examination of the patient should first be made and may include complaints of pain by the patient, digital palpation, use of neurocalometer, caligraph, X-rays, and any other available appliances useful for that purpose.

The headrest to be utilized in my method may be applied to any of the common types of chiropractic tables either those with horizontal top or the kneeling forms of tables with raised head supports, and may be formed either separately and attached to the table or the base plate may be formed integral with the table top. It includes a rigid base with a movable top plate hinged or pivoted thereto and is provided with springs or other resilient means to raise the inner end of the top plate above the inner end of the base. Adjustable means are provided to regulate the distance to which the springs may raise the inner end of the top plate from the inner end of the base and stops or detents are provided which automatically will lock the top plate in its lowermost position when driven downwardly by the force of the operator in giving an adjustment.

In the headrest as used in the method described, when helical tension springs are utilized means are provided for adjusting the position or tension of the springs in order to either increase or reduce the amount of force necessary to be applied by the operator upon the applicable portion of the patient's head and neck to cause the top plate of the headrest to come into contact with the stops or base thereof, thus making provision whereby various degrees of force may be applied by the doctor in administering an adjustment.

Until the present time all side posture chiropractic tables designed for upper cervical adjusting (referred to as "specific chiropractic adjusting"), intended for employment of the "toggle recoil" for the removal of nerve pressure in the atlas-axis region, have one thing in common, viz: the headrests, which can be adjusted for the relaxation and comfort of the patient, are, during the adjustment, completely immovable so that the adjustment by recoil has been dependent solely upon the skill of the operator with no aid from the table in any respect.

My method involves the use of a headrest having a movable top plate which permits the operator during the thrust, to move the head or neck downwardly through a limited space which terminates at a fixed distance, in turn causing proper movement of parts in the upper cervical region never before experienced in chiropractic history.

The top plate of the head piece may be supported upon the base plate as a rocker in or near its center with tension or similar springs between the plates at the outer end, or the top plate and fixed base plate may be hinged together at or near the outer end of the top plate, and springs applied to the inner ends of the plates.

The tension or pressure of the springs can be adjusted

to increase or lower the resistance to movement of the top plate while the distance between the plates at the inner end may be regulated in order to increase or decrease the distance the head travels in receiving the adjustment.

When the adjustment is being made, as the head or neck descends there will be increased resistance of the springs. When the head and neck have completed their travel, the top plate and base are provided with means to lock them together, thus preventing the top plate from coming up again until released by the operator, thus permitting the operator to complete the toggle and deliver the proper movement before releasing the top plate.

In the exercise of my invention, any one of the common forms of chiropractic tables, when fitted with such a resilient headrest, may be utilized to support the patient thereon either lying upon one side or kneeling with his head and neck resting upon the headrest in horizontal position and with one ear inserted in a longitudinal channel of the headrest provided for that purpose.

In cervical cases I attain the objects stated by preferably positioning the patient with one side of his head and neck resting upon the headrest and one ear in the channel mentioned for that purpose, and with the mastoid-temporal regions of the patient resting upon the inner or movable end of the head rest on opposite sides of the channel; adjusting the headrest to provide the desired limitation of upward motion produced by the springs and to limit the downward motion of said movable end produced by the adjusting force; applying point one of the nail hand of the operator to the surface of the neck or head of the patient at or near as possible to the upper end of the transverse process of the atlas or axis; giving a quick forcible downward pressure of the nail hand upon the part contacted, including torque if indicated, and with the toggle movement of the hands and arms of the operator all performed in accordance with the standard generally accepted practice of the chiropractic profession and as described in such books as "The Subluxation Specific—The Adjustment Specific" and other standard works.

In this specification, I use the term "nail hand" as used in said book to indicate the hand of the operator applied directly to the proper place in the neck of the patient. I use the term "point one" to indicate the end of the pisiform bone of the nail hand or wrist, and the terms "torque" and "toggle" to indicate the motions described in said book which have become standard practice of the chiropractic profession.

In delivering such adjustments, the nail hand is placed in the position indicated and the other hand, which is called the "hammer hand" is applied to the nail hand and the power of both hands and arms is utilized in delivering the adjustment.

Quoting from the above mentioned book, it is well recognized that

"introducing invasionary speed to live man and he resists with recoil speed, which speedy resistance adjusts the subluxation. Innate cannot recoil on slow movement induced by shove or push. She recoils only where there is necessity for a rebound. She will recoil on a quick delivery of forces approaching invasion, or following invasion. Adjustment with 'that extra something with staying-put value' is the correction made by Innate on its recoil rebound to a speedy invasionary force." (Page 420.)

"Adjusting vertebra ('the adjustment with that extra something') is what happened after my hands have left the back; it is that reaction that occurs when the innate recoils in body of patient, which resets vertebrae into normal position." (Page 426.)

"An adjustment-adjustment where we deliver a light, quick recoil concussion of force, letting Innate absorb and recoil in retaliation; knowing Innate will adjust to correct normal position where it belongs and will best stay for longest possible time." (Pages 427-428.)

"If the Chiropractor will work to secure an Innate adjustment ('the adjustment with that extra something'),

utilizing his forces merely as a means to an entree to get Innate to make the adjustment, he will find that the subluxation will stay adjusted more permanently than before." (Pages 427-428.)

5 "An adjustment is that which Innate will adjust itself to. If it needs a violent jar to recoil the vertebra into alignment, then Innate will give it. If it needs a 'light' readjustment, Innate will perform it." (Page 430.)

The danger of overadjustment is generally well recognized. In the book mentioned, it is said:

10 "The adjustment for any and all torqued subluxations will be with nail point one upon either transverse process of atlas or axis spinous process. Great emphasis is now being laid to see that it is nail point one, of nail hand, 15 that is used." (Pp. 431-432.)

"An adjustment consists of just so much and not any more; but it must be that 'just so much.' If there are no locks to prevent atlas wedge-side-slipping to the right, and no locks to prevent its being adjusted to median line, then it is certain that there are no locks on the other side to prevent its being over-adjusted to left.

20 " * * * If atlas rides dead center there will be no pressure-interference at inter-magnum-atlas foramen. Axis, to be normal, must ride its odontoid in normal relation 25 to fovea dentalis; neither posterior, left nor right. * * *" (Page 440.)

20 "If, however, an 'adjustment' is given upon an atlas wedge-side-slip in a slow, shove, push manner, it can be made to go beyond normal median line, but Innate not recoiling, it will not snap back into median line and stays beyond, where it should not have been shoved or pushed." (Page 442.)

30 For the reasons given above, it is of great importance that the force of nail point one as applied may be increased by the momentum of the nail hand at point one 35 traveling the given distance during its application. It is also of importance that the axis or atlas will also be caused to travel some distance and to accumulate a certain amount of momentum before the contact of the 40 top of the headrest with its base stops the movement of the top of the headrest.

45 After traveling some distance the downward movement of the headrest is definitely and abruptly stopped at a predetermined point in accordance with previous adjustment thereof, and this fact gives an increased suddenness to the action of the nail point upon the atlas or axis. As soon as the downward movement is stopped, the headrest is automatically locked in its lowermost position and it cannot interfere or obstruct the natural recoil of the parts which takes place when the hands of the operator are instantly removed at the conclusion of a swift thrust.

50 It is difficult to understand and explain just why momentum produces a valuable effect in moving the vertebrae, but extended experience has demonstrated that it does have an important part in producing the direct movement as well as the torque movement of the vertebrae and to some extent the pressure of the nail point is cushioned in its movement downward. In the same way it avoids or reduces the pain which may be caused when that cushioning effect is absent.

55 Likewise, the recoil of the tissues surrounding the vertebrae is aided by the fact that the top of the headrest is automatically locked to its base at the lower end of the stroke of the operator and cannot travel upwardly until released by the operator.

60 My type of recoil adjustment, from a technical standpoint, differs considerably from the recoil produced by the conventional headrest now in common use, because my headrest will facilitate a high rate of speed of the hands of the operator in delivering an adjustment and will also permit a smaller degree of force to be effective when applied to the cerebral region in question.

65 I do not limit my process to the use of either tension or compression coiled springs, but it is obvious that

various equivalent forms of springs, such as blade or plate or forked springs may be substituted for helical springs and can be made adjustable to produce the same effects.

Likewise, the base plate of the headrest may be formed as an integral part of the table or rigidly secured in a given position thereon with the movable top plate pivoted thereto.

Various modifications may be made in the speed, force applied, distance traveled by the head or neck of the patient or the hands of the operator, and in the apparatus utilized to aid in carrying out my method without departing from the spirit of my invention as described in the claims and I do not limit my claims to the precise language thereof.

I claim:

1. The method of adjusting subluxations of the upper members of the cervical vertebrae, including positioning the patient with his head and neck in lateral horizontal position and resting upon a headrest having a fixed base and a movable top plate pivotally mounted thereon with the inner end of the top plate resiliently supported whereby a short downward movement of the top plate may be allowed, and also having a definite stop to positively stop such downward movement after a certain distance of travel, and locking means to automatically and rigidly secure the top plate of the headrest at its lowest point of travel, then applying by the hand or hands of the operator to the portion of the neck overlying one of the lateral transverse processes of the atlas or axis a conventional downward adjustment force and removing the hands after continuing for an instant after the top plate has been stopped.

2. The method as described in claim 1, with means for locking the top plate in its lowest position thereby acting to permit free recoil of the parts affected by the downward thrust as soon as the hands of the operator or pressures therefrom are removed.

3. A process or method of chiropractic adjustment (to be applied after taking X-ray spinographs of the patient by which the location, extent, and nature of any subluxation or misalignment in the upper cervical region of the spine of a human being has been shown), which method includes the following steps: (a) placing the patient in a reclining position with the head and neck resting laterally upon a headrest having means for permitting a short

downward movement of that portion of the head and neck surrounding the subluxation or displacement and for causing a sudden stoppage of such movement at a given point; (b) then applying the nail hand of the operator to the surface of the neck overlying one of the lateral transverse processes of either the atlas or axis; (c) exerting an adjusting force thereon; and then (d) removing the hands thus releasing the pressure as soon as the downward movement of the nail hand has been stopped.

4. A process or method of chiropractic adjustment to be applied after examining the patient by any of the means in common use by chiropractors to determine the location, extent and nature of any subluxation or misplacement in the upper cervical region of the spine of a human being, which method includes the following steps: (a) positioning the patient in a lateral reclining position with the head and neck resting upon a movable top of a headrest having means for permitting a short downward movement thereof and for causing an abrupt stoppage of such movement at the lower end thereof and with means automatically locking the movable top of the headrest in its lowermost position; (b) then applying the nail hand of the operator to the portion of the neck overlying one of the lateral transverse processes of either the atlas or axis; (c) exerting a quick adjusting force thereon; and (d) removing the hands thus releasing the pressure instantly when the adjusting movement of the nail hand has been completed.

5. A process or method of chiropractic adjustment to be applied after examining the patient, which method includes the following steps: (a) placing the patient in a lateral reclining position with the head and neck resting upon a movable headrest adapted to permit downward movement and to cause a sudden stoppage of such movement with means for automatically locking the headrest in its lowermost position; (b) applying the nail hand of the operator to the neck adjacent one of the lateral transverse processes of either the atlas or axis; (c) exerting a swift downward force thereon; and (d) releasing the pressure as soon as the downward movement of the nail hand has stopped.
